NEW JERSEY.

BOILER CONSTRUCTION.

Application filed January 12, 1924. Serial No. 685,909.

Our invention relates to a boiler and the method of manufacturing it and more particularly pertains to a construction comprising, preferably and as exemplified by the 5 drawings, a copper cylindrical surface carrying at its ends cast metal heads.

We are well acquainted with the highly intensified development of this art as evidenced by our familiarity with the following 10 list of patents; Wilson et al. No. 24772 of 1859, British Cope No. 2429 of 1860, Bruson No. 132,895 of 1872, Scaife No. 6,391 of 1875, Budke No. 192,358 of 1877, Caird No. 473,495 of 1892, Booth No. 516,073 of 1894, 15 Trust No. 532,117 of 1895, Reynolds No. 621,540 of 1899, Patterson No. 674,305 of 1901, McSherry No. 690,312 of 1901, British LeFebvre No. 8440 of 1906, Hardie No. 814,375 of 1906, Hardie No. 826,847 of 1906, 20 Stollberg No. 880,834 of 1906, Reynolds No. 881,951 of 1908, Young No. 891,895 of 1908 and Draper No. 1,125,011 of 1915.

What is known as a copper boiler has many generally acknowledged advantages 25 over iron boilers which we have long used in our business, but the manufacturers of copper boilers have been confronted with many difficulties, their cost has been disproportionately high and many have proven 30 unsatisfactory. After considerable experiment we have successfully solved the problem. Previous copper boiler constructions included one in which the heads were spun to shape and then threaded spuds for suitable pipe connections were screwed and soldered into place, however, the spuds were rarely set truly in consequence of which the pipes were not straight or parallel, moreover, the bottom head had to be provided 35 with a large tapped hole to permit the insertion of riveting tools for effecting connection between the ends of cylindrical section and the heads, after which a reducing bushing had to be screwed into the large hole to bring it to its required size. Another earlier 40 type of copper boiler included top and bottom halves each drawn as one piece, but these were very expensive and did not avoid the trouble from disaligned or non-parallel 45 pipe hole fittings.

One object of our invention was the provision of cast heads which would make possible the machining and tapping of parallel 50 holes which would reliably maintain such relationship, but we learned that the heads

tended to belly-out under test pressure with the result that the outwardly projecting edge collar (admittedly old in the art) had its circular junction corner turned inwardly under expectable or required pressure. In 60 consequence of the bellying-out of the head as a bending action, and the attendant withdrawal of the outer surface of the outwardly projecting collar from the shell a leak occurred at the seam therebetween because of 65 the deformation and dislocation of one or both of the parts. The heads should be of spherical conformation, the radius of spherical curvature being determined by a standard formula according to the diameter of 70 the head. We have also learned by experiment that copper shells cannot successfully have their seams welded because the welding heat weakens the copper to such a great extent. Cylindrical copper shells have been 75 marketed with brazed seams, but the heat of brazing anneals the copper necessitating that the shell be subsequently hardened by a process of rolling, which however, never brings it back to its original toughness. We rivet 80 our shell seam and at a subsequent stage of manufacture cover the rivets interiorly with solder. One of the prime features of our construction, which demonstrates progress from failure to success, is the provision of 85 an inwardly projecting collar, that is to say, a collar extended from its circular line of junction with the head in a direction toward the middle of the boiler. We have discovered that the length of this additional inwardly projecting collar should vary according 90 to the diameter of the shell, being longer in proportion as the diameter of the shell increases. Pressure against the heads increases very rapidly as the diameter of the 95 head increases. The thickness of the metal parts particularly the thickness of the inwardly projecting collar may likewise vary by being increased for the larger sizes.

The manufacturing procedure which we 100 have adopted, or the series of steps in the method of assembly is as follows:

We first rivet the overlapping longitudinal shell seam, next turn an inwardly projecting bead on the shell near each end for the 105 lower edge of the inwardly projecting collar to rest on, then tap holes in suitable cast heads and also machine both inner and outer surfaces on the duplex collar formation which borders the rim of the head, after 110

which we insert one head in place and clench one extremity of the shell around the outwardly projecting collar, thereafter we cover the rivets interiorly with solder through the opposite still open end of the boiler, then similarly clench the other head in place and finally fill the outer corners between the outside of the shell and the opposed or near surfaces of the outwardly projecting collar 10 and bent extremity of the shell with solder.

Adverting to the drawings:

Figure I is a diametrical section of one end of an experimental boiler construction which we discovered to be unsatisfactory.

Figure II is a corresponding view of the construction shown in Figure I after being subjected to a test pressure.

Figure III is a diametrical section of one end of another experimental boiler construction which also proved to be unsatisfactory.

Figure IV is a corresponding view of the construction shown in Figure III after being subjected to a test pressure.

Figure V is a longitudinal sectional view 25 of a boiler embodying our invention.

Figure VI is an interior plan view of the boiler head shown in Figure V.

Figure VII is a diametrical section of one end of a simplified modification of our invention.

Figure VIII is a plan view of the inner side of the boiler head shown in Figure VII.

In attaining a successful development of a copper boiler, we first held in mind the desirability of having the holes, usually tapped so as to be suitable for pipe connections, reliably straight and parallel, and accordingly, proposed the use of cast heads which could be accurately fashioned with 40 tapped holes having the desired relationship with respect to each other. We early tried a construction such as shown in Figure I wherein a cylindrical copper shell 1 had fitted into each end a cast head 2 provided 45 with an exteriorly projecting collar 3 of the chime wall type around which the annular end 4 of the shell was clenched. When test pressure was applied the head bellied out as shown in Figure II to cause a distortion of 50 it as well as a dislocation of the collar 3 and of course resultant leakage.

We also experimented with a construction such as is shown in Figure III wherein a head 5 of relatively concave curvature was 55 set in one end of a shell 6 and was likewise fashioned around its rim with an outwardly projecting collar 7 around which the extremity 8 of the shell was clenched. Test pressure likewise caused a belllying-out of the 60 central portion of the head after the manner shown in Figure IV with attendant displacement of its collar 7 relative to the shell.

Later experiments eventually led to the 65 conception and successful adoption of heads

of the construction shown in Figures V and VI, characterized by the provision around the rims thereof of what may be termed a duplex collar or else regarded as a collar projecting in opposite directions from its 70 line of junction with the head. For larger sizes of boiler we have thought it additionally expedient to reenforce the head on its inside with ribs which would exert a direct thrust against the additional and supposedly 75 new collar formation which projects toward the middle of the boiler, and have therefore shown such rims in our technically preferred embodiment. However, it is to be clearly understood that we have manufactured and 80 successfully used heads as disclosed in the simplified modification of Figures VII and VIII in boilers having diameters of twelve, fourteen and sixteen inches where they have withstood a three hundred pound pressure.

It is established that boiler heads should preferably have a spherical surface conformation and our heads have it. Where the spherical surface terminates, that is to say,

at the circular lines of junction therewith of 90 our collar formation the latter has a general cylindrical shape, or in other words, neither the inwardly or outwardly projecting portions of the collar construction are continuations of the spherical curvature.

Instead 95 of having the annular corner between a head and its peripheral outwardly projecting collar rest upon an inwardly turned bead of the shell, we have the extremity of our inwardly projecting collar rest upon such a 100 bead.

The provision of the additional inwardly projecting collar which conforms to the inside of the shell interiorly of the completed boiler is, we are convinced, the step 105 from failure to success. The inwardly projecting collar on the head or that one which extends toward the middle of the boiler is 110 therefore a feature of our invention known to have decided value by constituting a reenforcing element for resisting any tendency on the part of the middle of the head to deflect outwardly.

A ring being the strongest form for subjection both to tension and compression is a factor which contributes to the 115 desired realization.

A copper blank is rolled to form a cylindrical shell 9 having two longitudinally extending edge portions 10 and 11 lapped, the latter upon the former, and secured together by a row of rivets 12 as clearly shown in Figure VI. At a later stage of the manufacturing procedure the rivets 12 will be interiorly coated with solder 13 whereby to effect a sealed closure at the lapped seam. A pair of inwardly projecting beads 14 are 125 then turned around the shell corresponding distances from and rather near opposite ends thereof as may be seen upon scrutiny of Figure I.

A head 15, which may be formed as a cast 130

bronze alloy conforming generally to a spherical surface is adapted for snug insertion in the end of the shell. The head 15 is provided with three outwardly projecting bosses 16, 17 and 18 which are fashioned with tapped holes 19, 20 and 21 respectively, and with which suitably threaded pipe connections may be made. Merging integrally with the annular rim or border of the spherically shaped central portions of the head 15 we provide what may be described as a duplex collar composed of an outwardly projecting collar 22 and an inwardly projecting collar 23 the outer lateral surfaces of both being machined at 24 to conform to a cylindrical surface of the same size as the interior cylindrical surface of the shell 9. The head 15 is inserted so that the inner annular edge 25 of the collar 23 rests against one of the beads 14. In this way the head may be accurately positioned preparatory to further interlocking its connection with the shell by clenching the end 27 of the shell 9 around the collar 22 and against the concave and preferably machined surface 26 thereof. Thereafter, the corners on the outside of the head between the outer surface of its body and the concave surfaces of both the collar 22 and the end 27 are filled with solder 28 which will serve to both seal and reenforce.

For certain larger diametrical sizes of boiler we provide heads fashioned interiorly with a central boss 29 from which a series of ribs or webs 30 extend radially outward whereby to provide an additional reenforcing agency.

It is after the one head has been secured in place, for instance, the head 15 as has already been described, that the rivets 12 may be interiorly covered with the solder 13, following which, another head 31, provided with two tapped bosses 32 and 33, is similarly inserted and interlocked with the opposite end of the shell 9 as disclosed in Figure V.

The modification shown on Sheet 3 is solely a simplification of the construction of the heads by the omission of the reenforcing ribs on the inside. Such a head 34 including the inwardly projecting collar 35 has proven satisfactory for the smaller sizes of boiler which we have manufactured and used.

We claim:—

1. A boiler comprising a cylindrical section, and heads each provided with annular projections extending in opposite directions, the ends of said section being interlocked with said heads respectively.
2. In a boiler construction the combination with a cylindrical section, of a spherically shaped head having its circular edge extended in opposite directions to form an annular rim having two free edges, the end of said section being clenched around one

end of said head so that its other edge is positioned interiorly of said section.

3. In a boiler construction the combination with a cylindrical copper section, of concavo-convex cast metal head having its circular extremity located within and projecting in opposite directions longitudinally of said cylindrical section, the confining end of said section being clinched around the outwardly projecting edge of said head. 75

4. The method of making a metal boiler which consists in bending a blank to cylindrical form, overlapping the longitudinal edges of said blank, riveting them together, fitting a doubly flanged head in the end of said cylinder, and then clenching the end of the cylinder around a flange of said head so that the other flange of said head conforms to and extends along an interior portion of said cylinder. 80

5. In a boiler, the combination of a cylindrical copper shell fashioned with an inwardly projecting bead, and a rigid cast metal head bordered by a collar adapted to fit in one end of said shell and extending toward the opposite end of the shell when fitted therein, the extremity of said collar resting against said bead, the extremity of said shell being clenched over the outside of said head. 90

6. In a boiler, the combination of a cylindrical shell fashioned with an annular inwardly projecting bead, and a head bordered by a duplex collar projecting in opposite longitudinal directions and adapted to fit in one end of said shell, one extremity of said collar resting against said annular bead, the extremity of said shell being clenched around the other projecting extremity of said collar. 100

7. A boiler comprising the combination of a cylindrical copper shell, cast metal heads each embracing a spherical surface and each fashioned on its annular edge as a collar projecting in opposite longitudinal directions from its circular line of junction with the body of its head, the outside surface of said collars being cylindrical and fitted in opposite ends of said shell, the extremities of said shell being clenched around remote edges of said collars for securing said shell and heads together. 110

8. In a boiler construction the combination with a cylindrical section, of a spherically shaped head having its circular edge projected in opposite directions to form an annular rim having two free edges, the cylindrical outer surface of said rim being disposed within said section and the two free edges of said rim being interlocked with said section against either direction of axial movement. 120

9. In a boiler a head provided with a pair of edge defining flanges projecting in opposite directions, and a body portion fashioned 130

with inward projections partially confining said flanges respectively.

10. In a boiler an annular head provided with a pair of peripheral flanges projecting in opposite directions within the mean cylindrical plane of said periphery, and a cylindrical body portion fashioned near one end with inward projections, one of said projections abutting the extremity of each of said

10 flanges.

11. In a boiler, an open shell, a head bordered by a chime collar and a thickened section of junction of said head and collar and also bordered by a collar projecting from

15 said junction section in an opposite direction with respect to said chime collar, one

end of said shell embracing both of said head collars fashioned with a bent portion abutting an edge of one of said collars.

12. In a boiler, an open cylindrical shell, 20 a circular cast metal head bordered by oppositely projecting collar sections together defined by a cylindrical surface, the extensive cylindrical surface outwardly defining said collar sections being machined and 25 adapted for a pressed fit in the open end of said shell and means for securing the parts in position.

Signed by us, this 20th day of December, 1923.

HERBERT J. LONG.

FREDERICK D. SCHNEIDER.
